STOCK REGULATOR FOR PAPER MAKING MACHINES

Filed March 13, 1926

Patented Mar. 1, 1927.

1,619,682

UNITED STATES PATENT OFFICE.

WILLIAM J. SHERIDAN, OF ROCHESTER, NEW YORK.

STOCK REGULATOR FOR PAPER-MAKING MACHINES.

Application filed March 13, 1926. Serial No. 94,567.

The object of this invention is to provide a device that will regulate the feed of stock to a paper making machine so as to secure a uniform feed of the stock to the end that 5 the machine will not clog up and the stock will be uniformly fed, and that paper of a uniform thickness will be made.

This and other objects of the invention will be fully illustrated in the drawing, described in the specification and pointed out in the claims at the end thereof.

In the drawing:

The drawing is a perspective view of my improved stock feed regulator.

15 In the drawing like reference numerals indicate like parts.

Reference numeral 1 indicates a vat having the sides 2, ends 3 and bottom 4. The vat is shown partly broken away. This vat 20 is divided by the partitions 5, 6 and 7. The partition 5 has an opening at the bottom thereof. The partition 6 has an opening about midway from top to bottom and the partition 7 has an opening near the top 25 thereof. These partitions divide off the vat into the compartments 9, 10, 11 and 12. The openings in the partitions allow the pulp to flow from the right hand side of the tank to the left hand side as shown in the drawing.

30 The pulp is pumped up through the feed pipe 8 into the compartment 9 and flows from there into the compartment 10 and from there into the compartment 11 from which, part of the pulp passes through the 35 opening 15 into the pipe 16 and the balance of it passes over into the compartment 12 from which it flows back into the vat where it is mixed with other stock and in time is again pumped through the feed pipe 8 and 40 is caused to go through the apparatus repeatedly until it passes into the pipe 16 as above pointed out. In the compartment 9 is provided a hollow float 20 which is rectangular in shape. The float is slightly 45 smaller than the compartment in which it is adapted to rise and fall. This float is carried upon a bracket 21 which is suspended from a walking beam 22 which is pivoted on a stud or spindle 23 which is supported 50 on a bracket 24 mounted on the partition 6. Beyond the spindle is provided a link 25, the upper end of which is threaded and passes through the walking beam 22. From the bottom of this link swings a tube 26 55 which loosely fits in the pipe 16 and acts as a loose fitting valve therein in connection

with the opening 15. In the far end of the walking beam 22 is an eye screw 27 to which is connected the springs 28 and 29 which are fastened to suitable stops above and below the walking beam by which the left hand end of the beam is normally held in a position that is substantially uniform but nevertheless permits the beam to swing within a small limit. The ends of the 60 springs 28 and 29 can be adjusted up or down so as to vary the normal position of the ends of the beams.

The bracket 21 is provided with holes in which are inserted pins 30. One of these 70 pins engages a suitable opening or bearing in the reduced end of the walking beam 22 so that when the end of the walking beam swings up or down the float will move to correspond, or when the float moves the 75 walking beam will swing to correspond. The float is made so that normally it will be about one-half submerged. The faster the stock flows into the pipe 8 and the thicker the stock will be, the higher the 80 float will stand in the compartment 9. As the right hand end of the walking beam 22 rises with the float the left hand end of the beam will swing down and carry with it the tubular valve 26 tending to close the opening 15 more and more thereby. When the float 20 falls the right hand end of the beam 22 swings down with it and the left hand end of the beam 22 swings up and raises the tubular valve 26 permitting more 85 stock to flow through the opening 15.

The stock that accumulates around the float usually becomes too thick and to offset this and keep it of the right consistency, I provide a water pipe 35 having a valve 36 90 therein which feeds water to the shower 37 which has a large number of small perforations therein from which water is sprayed onto the stock from above. This serves to keep the stock from getting too thick around 100 the float.

As the stock is fed up into the compartment 9, it varies in consistency due to uneven mixing in the vat. If the stock is too thick it will feed faster to the machine than 105 it ought and cause the paper to run thicker than it should. If the stock is too thin the pulp will feed slower to the machine and cause the paper to run thinner on the machine than it should be. My device operates to feed the paper stock uniformly and 110 secure the making of paper of uniform

thickness as follows. As long as the stock remains uniform in the compartment 9 the float 20 will stay at the same height. When the stock gets thicker in the compartment 9 the level of it rises and carries up the float 20 and in so doing the walking beam 22 swings so as to push the tubular valve 26 down in the pipe 16 partially closing the opening 15 and retarding the flow of stock 10 through said opening. This reduces the amount of stock that passes to the machine. The float will remain up as long as the stock remains too thick which may be until the whole vat is emptied. If the stock from 15 the next vat runs thin then the float 20 will drop causing the valve 26 to rise and this will permit more stock to flow to the machine.

If the machine is making tissue paper, less stock will be fed to the machine than if it is making paper of heavier grades. This necessitates an adjustment of the valve 26 which is provided for by means of the thumb nuts 40 and 41 which can be turned 25 to raise or lower the valve with reference to the walking beam 22. In this way the valve can be adjusted to feed the correct amount for paper of any desired thickness.

In an apparatus heretofore used each of 30 the compartments is about $22\frac{1}{2}$ inches high and 14 inches square except the last one which may be somewhat smaller than the others. It will be understood that the pulp will normally stand in the compartment 9, 35 several inches higher than in the compartment 10 and the pulp will stand in compartment 10 several inches higher than in compartment 11. To secure this distribution the opening at the bottom of partition 5 40 is made somewhat smaller than the opening in the partition 6. This will cause the stock to rise to a considerable height in the compartment 9 securing better regulation and less rapid changes in the position of the 45 float.

I have provided a pipe 50 with a valve therefor by which water may be discharged directly into the valve tube 26 through which it passes to mix with the stock in the 50 tube 16 to thin it out if necessary.

It will be understood that the compartment 10 and partition 6 may be omitted in which case the stock will discharge through the opening at the bottom of the partition 5 55 directly into the bottom of the compartment 11 and feed into the tube 16. In such case the walking beam 22 will be shortened up and the bracket 24 therefor will be fastened to the top of the partition 5. The 60 bracket 24 can be made with a quarter turn so as to rest on the partition 5 and avoid the pipe 37.

As illustrated in the drawing, the float 20 65 has a plate 20^A attached thereto. This plate extends beyond the side walls of the float

and forms a ledge or small flange 20^B around the float. In operation the float 20 is only partially submerged in the pulp or paper stock. The flange 20^B of the float being at the bottom is, however, totally submerged 70 and the liquid and pulp above it serves to retard the movement of the float as it rises and falls in the pulp. This prevents an erratic movement of the float due to sudden changes in the level of the pulp within the 75 vat.

I claim:

1. In an apparatus for regulating the flow of pulp, the combination of a vat having an outlet in the bottom thereof, a pipe mounted in said outlet and projecting into the inside of said vat, said pipe having an opening in the side thereof near the outlet of said vat, a second pipe suspended in said first pipe, and means for raising and lowering said second pipe in said first pipe to regulate the flow of pulp thru the opening in said first pipe into the outlet of said vat.

2. In an apparatus for regulating the flow of pulp, the combination of a pair of vats, 90 one of said vats having an inlet in its bottom and the other of said vats having an outlet in its bottom, a stationary pipe having an elongated opening in the side thereof mounted 95 in the outlet of said vat, a second pipe suspended within said stationary pipe, a float in the other of said vats, a walking beam connecting said float with said second pipe to raise and lower said second pipe within said stationary pipe with relation to the 100 movement of said float.

3. In an apparatus for regulating the flow of pulp with relation to its consistency, the combination of a vat, a partition separating said vat into two compartments, an inlet 105 in the bottom of one of said compartments and an outlet in the bottom of the other of said compartments, a stand pipe having an opening in the side mounted in the outlet of said compartment, a movable pipe suspended within said stand pipe and adapted to regulate the flow of pulp thru the opening into said stand pipe, a float suspended in the other of said compartments 110 and means connecting said float with said movable pipe to raise or lower said pipe relative to the movement of said float, a water supply feeding a predetermined volume of water into said compartment around 115 said float.

4. In an apparatus for regulating the flow of pulp with relation to its consistency, the combination of a vat, a partition separating said vat into two compartments, an inlet in the bottom of one of said compartments and an outlet in the bottom of the other of said compartments, a stand pipe having an opening in the side mounted in the outlet 125 of said compartment, a movable pipe suspended within said stand pipe and adapted 130

to regulate the flow of pulp thru the opening into said stand pipe, a float suspended in the other of said compartments and means connecting said float with said movable pipe

- 5 to raise or lower said pipe relative to the movement of said float, a water supply feeding a predetermined volume of water into said compartment around said float, a second water supply feeding water into said
- 10 standpipe to dilute the pulp passing from the compartment thru the opening in said standpipe.

5. In an apparatus for regulating the flow of pulp, the combination of a pair of vats,

- 15 one of said vats having an inlet in its bottom and the other of said vats having an outlet in its bottom, a stationary pipe having an elongated opening in the side thereof mounted in the outlet of said vat, a second pipe suspended within said stationary pipe, a float in the other of said vats, a walking beam connecting said float with said second pipe to raise and lower said second pipe within
- 20 said stationary pipe with relation to the movement of said float, a third vat interposed between said pair of vats, said third vat having an opening adjacent to its bottom and leading from one of said pair of vats and an opening in the side of said third vat, a predetermined distance above its bottom and leading into the other of said pair of vats above the bottom thereof, an overflow leading from said last
- 25 named vat.

- 30 6. In an apparatus for regulating the flow of pulp, the combination of a pair of vats, one of said vats having an inlet in its bottom and the other of said vats having an outlet in its bottom, a stationary pipe having an elongated opening in the side thereof mounted in the outlet of said vat, a second
- 35 pipe suspended within said stationary pipe, a float in the other of said vats, a walking

beam connecting said float in the other of said vats, a walking beam connecting said float with said second pipe to raise and lower said second pipe within said stationary pipe 45 with relation to the movement of said float, a third vat interposed between said pair of vats, said third vat having an opening adjacent to its bottom and leading from one of said pair of vats and an opening in the side of said third vat, a predetermined distance above its bottom and leading into the other of said pair of vats above the bottom thereof, an overflow leading from said last

55

7. In an apparatus for regulating the flow of pulp, the combination of a regulating valve, a float controlling the operation of said valve, a flange surrounding said float below the top thereof and adapted to make 60 the pulp and water surrounding said float above said flange retard the movement of the float.

8. In an apparatus for regulating the flow of pulp, the combination of a pair of vats, 65 an inlet in one vat and an outlet in the other vat, a float in the vat having the inlet and a regulating valve in the vat having the outlet, said regulating valve comprising a tube forming a continuation of said outlet 70 within said vat, a cylinder of reduced diameter in said tube, said tube having an opening in the side thereof, a connecting beam fulcrumed between said vats and connecting said float with said cylinder and adapted to hold said cylinder suspended within said tube and move it up or down opposite to the opening in said tube to control the flow of the pulp from the vat into the outlet.

In testimony whereof I affix my signature.

WM. J. SHERIDAN.
